UNITED STATES PATENT OFFICE.

GEORGE H. BRUDER, OF WEYMOUTH, MASSACHUSETTS.

DIRECTION SIGNAL.

Application filed November 6, 1925. Serial No. 67,379.

This invention relates to travel signals for vehicles and has for its object to provide an article of this nature by means of which a signal may be conveniently set to indicate a turn to the left, a turn to the right or a stop.

In the present invention, an arrow is provided which may be operated to point to the right or left, as may be desired, and a target is provided which may be swung into view to indicate a stop.

In the drawings:

Figure 1 is a side elevation of the invention with a portion broken away.

Figure 2 is a vertical longitudinal section.

Figure 3 is vertical section of a detail.

Figure 4 is a view similar to Figure 3 with certain parts omitted.

Figure 5 is a detail in perspective with a portion broken away and

Figures 6 and 7 are fragmentary details in perspective.

Primarily, this invention comprises a frame in which a preferably arrow-shaped semaphore and a target are mounted, the same being so arranged that they are normally concealed from view. The arrow is divided into two parts, one having the usual heads or pointed end, and the other having the usual tail or notched end. These parts are so arranged that, upon manipulation of a lever, the two arrow parts may be projected from the frame so that the completed arrow, thus formed, will point either to the right or to the left, as may be desired. The target is so mounted that it may be projected into view, upon manipulation of a second lever.

Referring to the drawings, the signal includes a frame 7 having side plates 8 and 9 and a connecting top portion 10, the lower portions of the side plates being turned at right angles as shown at 11 to receive the tubular member 12, at the outer end of which is a laterally extending socket 13.

Passing through the sides plates 8 and 9 of the frame 7 is a bar 14 on which is mounted a spacing tube 15. Surrounding the spacing tube, for a portion of its length, is a sleeve 16, the ends of which are reduced as shown at 16'. A gear 17 is fixed upon one of the reduced ends and head part 18, of an arrow is fixed upon the other. It will be noted that the sleeve 16 is free to turn upon

the spacing tube 15. Loosely mounted upon the sleeve 16 and connected together, are tail part 19 of the arrow, and a gear 20, while upon the spacing tube 15, between the head part 18 and the adjacent wall of the frame, there is loosely mounted a target 21, having a gear 22 attached thereto. In order to impart stability to the bearing ends of the arrow part 18 and the target 21, collars 18' and 21' are attached thereto, respectively. Spacing washers may be mounted between the various moving parts, as shown in Figure 3.

In order to operate the two arrow sections so as to project them outwardly of the casting or frame, an oscillating lever 23 is provided, this lever being mounted, at its center, on a pivot connected to the side plate 8. Near the upper end of the oscillating lever 23, is a slot 39, the lower wall of which is stamped so as to project slightly out of the plane of the lever and is provided with teeth forming a rack 25. The upper extremity of the oscillating lever is bent over and then downwardly and is provided with 75 teeth to form a rack 26 which is spaced away from the lever and extends beyond the rack 25, as is clearly shown in Figure 6. By reference to Figure 3 it will be noted that the rack 25 is in engagement with the gear 17, while the rack 26 rests in engagement with the gear 20.

In order that the target may be operated to project outwardly of the frame 7, an oscillating lever 27, similar to the oscillating lever 23, is pivoted to the side plate 9 on the pin 24 and is provided with a slot 28 and an outwardly projecting rack 29, the parts 28 and 29 being duplicates of the parts 39 and 25 of the lever 23 and being clearly shown in Figure 7. The rack 29 is in engagement with the gear 22.

In order that the levers 23 and 27 may be oscillated, reciprocating levers 23' and 27' are provided, the former being pivotally connected to the lower end of the lever 23, and the latter being connected to the lever 27 in like manner. The levers 23' and 27' extend longitudinally within the tube 12 and have their inner ends pivotally connected 100 to the operating levers 30 and 31, respectively. These operating levers pass through the socket 13 and are pivoted thereto, as shown. It will be noted that the operating levers are connected to the reciprocating levers by 110

means of pivot pins 32 which are of greater diameter than the thickness of the respective levers and are formed on suitable blocks which are held in recesses in said levers.

5 In order that the reciprocating levers 23' and 27' may be held in position, a guide plate 33 is provided, this being mounted upon the rod 34 which passes through the tube 12. This guide plate is provided with 10 slots through which the reciprocating levers pass.

It is necessary that the arrow sections and the target be held in their predetermined positions and for this purpose the reciprocating levers 23' and 27' are notched, as shown in Figure 5, the notches of each lever being adapted to receive rollers 35 mounted upon spring detents 36 having an end wrapped around the connected end of the 20 guide plate 33 and attached thereto, whereby they are held in position.

The operation of the device is as follows: If it is the intention of the driver to make a turn to the left, he swings the operating 25 lever 30 to the left. This moves the reciprocating lever 23' to the right which swings the upper end of the oscillating lever 23 to the left. The rack 25 then imparts motion to the gear 17, while the rack 26 imparts 30 motion to the gear 20, thus causing the arrow sections 18 and 19 to rise outwardly of the frame, in opposite directions, to form a completed arrow pointing to the left, as shown in full lines in Figure 1. When a 35 right hand turn is intended, the operating lever 30 is moved to the right and the direction of the movement of the parts is then reversed, which causes the sections of the arrow to swing upwardly so that the 40 completed arrow will point to the right as indicated in Figure 1, wherein the arrow parts are shown in dotted lines ascending into this position. When it is the intention of the driver to stop, the operating lever 45 31 is moved to the left which causes the reciprocating lever 27' to move in the opposite direction, thus rocking the oscillating lever 27 which, through the medium of the rack 29, imparts motion to the gear 22, 50 which causes the target to swing into view, the same being connected to the said gear.

What is claimed is:

1. A signal device for vehicles, including a frame, signal sections mounted within the 55 frame, and means operable in one direction for simultaneously projecting the signal sections from the sides of the frame, to form a completed signal, pointing in one direction, said means being operable in the opposite direction for projecting the signal sections in reverse order to form a completed signal pointing in the other direction.

2. A signal device for vehicles including a frame, signal sections mounted within the 60 frame, and means for simultaneously pro-

jecting the signal sections, selectively, from either side of the frame, in opposite directions, to form a completed signal.

3. A signal device for vehicles including a frame, a signal comprising signal sections 70 mounted within the frame, means for simultaneously projecting the signal sections, selectively, from either side of the frame, in opposite directions, to form a completed signal, a second signal mounted within the 75 frame, and means for projecting said second signal from the frame.

4. A signal device for vehicles including a frame, a signal comprising signal sections 80 mounted within the frame, means for simultaneously projecting the signal sections, selectively, from either side of the frame, in opposite directions, to form a completed signal, a second signal mounted within the 85 frame, means for projecting said second signal from the frame, and means for releasably holding the signals in their projected positions.

5. A signal for vehicles including a frame, 90 a signal including an arrow-head and an arrow-tail section mounted for oscillation within the frame, an oscillating lever mounted within the frame and geared with both of said signal sections, and means movable in one direction for rocking the oscillating lever in one direction to project the sections from opposite sides of the frame, and movable in the opposite direction to project the said sections in reverse order 95 from the opposite sides of the frame. 100

6. A signal device for vehicles including a frame, signal sections mounted within the frame, a pinion connected to each of said signal sections, an oscillating lever having 105 a depending rack and an upwardly projecting rack in mesh with said pinions for rocking the signal sections, and means operable in one direction for rocking the oscillating lever to cause the extension of said sections from opposite sides of the frame, in one order, and operable in the opposite direction for rocking the oscillating lever to cause the extension of the sections in a reverse order. 110

7. A signal device for vehicles including 115 a frame, signal sections and a signal rockably mounted within the frame, oscillating levers geared to said sections and signal, a support for said frame, reciprocating levers connected with said oscillating levers and extending within said support, spring detents mounted within the said support for engagement with said reciprocating levers and operating levers pivoted to said reciprocating levers and projecting from said support. 120

In testimony whereof, I affix my signature.

GEORGE H. BRUDER.
